(57) **CLAIM**

The ornamental design for a square latch box, as shown.

DESCRIPTION

FIG. 1 is a front perspective view of a latch box constructed in accordance with, and embodying, the principles of the present invention;

FIG. 2 is a rear perspective view of the latch box depicted in FIG. 1;

FIG. 3 is a front elevational view of the latch box depicted in FIG. 1;

FIG. 4 is a rear elevational view of the latch box depicted in FIG. 1;

FIG. 5 is a left side elevational view of the latch box depicted in FIG. 1;

FIG. 6 is a right side elevational view of the latch box depicted in FIG. 1;

FIG. 7 is a bottom plan view of the latch box depicted in FIG. 1; and

FIG. 8 is a top elevational view of the latch box depicted in FIG. 1.

The surface(s) or portion(s) of the article not shown in the drawing or described in the specification form(s) no part of the claimed design.

UNITED STATES PATENT AND TRADEMARK OFFICE
CERTIFICATE OF CORRECTION

PATENT NO. : Des. 531,485 S
APPLICATION NO. : 29/220497
DATED : November 7, 2006
INVENTOR(S) : James L. Cutler et al.

Page 1 of 2

It is certified that error appears in the above-identified patent and that said Letters Patent is hereby corrected as shown below:

In the Description, at line 16, please change:

“a top elevational view” to -- a top plan view --

In the Drawings

The drawing sheet 2 of 7 consisting of Fig(s) 3 should be deleted and substitute therefore the attached drawing sheets consisting of Fig(s) 3.

Signed and Sealed this

Thirteenth Day of February, 2007

A handwritten signature in black ink, appearing to read "Jon W. Dudas". The signature is written in a cursive style with a large, stylized "J" and "W".
